Joseph M. Katz, Pittsburgh, Pa., assignor to The Paper-craft Corporation, Pittsburgh, Pa., a corporation of Pennsylvania

Application November 12, 1957, Serial No. 48,426

Term of patent 7 years

(Cl. D58—12)

Fig. 1.

Fig. 2.

Fig. 1 is a front perspective view taken from the left side of a ribbon dispenser package showing my new design; and

Fig. 2 is a rear perspective view thereof taken from the right, with the spools omitted for convenience of illustration only.

The stippling on the drawing represents a contrasting colored area.

I claim:

The ornamental design for a ribbon dispenser package, as shown and described.
